US00D847536S

(12) **United States Design Patent** (10) **Patent No.:** **US D847,536 S**
(45) **Date of Patent:** **** May 7, 2019**

(54) **MAT**

(71) Applicant: **Varidesk, LLC**, Coppell, TX (US)

(72) Inventors: **David Patton**, Flower Mound, TX (US); **Coco Chang**, Lewisville, TX (US)

(73) Assignee: **Varidesk, LLC**, Coppell, TX (US)

(**) Term: **15 Years**

(21) Appl. No.: **29/582,578**

(22) Filed: **Oct. 28, 2016**

(51) LOC (11) Cl. **06-11**

(52) U.S. Cl.

USPC **D6/582**

(58) **Field of Classification Search**

USPC D6/582-589, 592-594, 596; D12/203, D12/608; D23/261; D32/55, 57; D3/304; D7/550.1, 553.1, 553.2, 553.3, D7/553.7, 554.3

CPC A47G 23/0303; A47G 27/00; A47G 27/02; A47G 27/0206; A47G 27/0212; A47G 27/0225; A47G 27/031; A47G 27/0293; A47G 9/062; A47L 23/26; A63B 21/4037; A63B 6/00; G09B 19/0015; F16N 31/006

(57) **CLAIM**

The ornamental design for a mat, as shown and described.

DESCRIPTION

FIG. 1 is a front perspective view of a mat, according to the new design.

FIG. 2 is a front elevational view thereof.

FIG. 3 is a rear elevational view thereof.

FIG. 4 is a right side view thereof.

FIG. 5 is a left side view thereof.

FIG. 6 is a top plan view thereof; and,

FIG. 7 is a bottom plan view thereof.

The features shown in broken lines are environment only, and not part of the claimed design.

1 Claim, 5 Drawing Sheets
